5253

PATENTED SEP 5 1871

Wm. H. Coffin
Attala, Miss.

UNITED STATES PATENT OFFICE.

WILBUR F. LANE, OF BOSTON, MASSACHUSETTS.

DESIGN FOR BURIAL-CASKET.

Specification forming part of Design No. 5,253, dated September 5, 1871.

To all whom it may concern:

Be it known that I, WILBUR F. LANE, of Boston, in the county of Suffolk and State of Massachusetts, have invented and produced a Burial-Case of a new, useful, and original shape or configuration, of which the following is a specification:

In the drawing, Figure 1 is a cross-section, and Fig. 2 a longitudinal section of a burial-case of my improved shape or configuration. Figs. 3 and 4 are vertical cross-sections of burial-cases, each of which has the same shape or configuration, except as to the molding and paneling and that the ends are square. Fig. 5 is a longitudinal section of a burial-case of the same shape or configuration as Fig. 2, except that the ends are square.

In the drawing, D is the lid, and E the bottom of the burial-case. A, B, and C are the sides, and A' B' C' and A'' B'' C'' the ends.

The main feature of novelty of my improved shape or configuration consists in the inclination of the two parts A and C (or A' and C', &c.) with respect to the part B, (or B', &c.,) so that the vertical cross-section or longitudinal vertical section of the burial-case shall be octagonal; a section through x x, (Figs. 1 and 2,) would also be octagonal, as the two ends of the case shown in these figures are three-sided, whether considered

vertically—*i. e.*, from D to E, or horizontally—that is, from B to the part directly opposite and corresponding to B.

It is not new to incline the part A (or A', &c.) to the part B, (or B', &c.,) and this is frequently done in burial-cases where the part B (or B', &c.) is continued until it reaches the bottom E, the sides (and ends) containing only two parts corresponding exactly to the parts A and B (and A' B', &c.,) except that the part corresponding to B is necessarily wider than B'—that is, wide enough to take the place of both B and C.

The molding or paneling may, of course, be varied, and the ends may be made three-sided or square.

The usefulness of my improved shape or configuration will be obvious to all familiar with the manufacture of burial-cases, more especially in preventing waste of stock; and it is believed, in point of appearance, to be much superior to any style of burial-case now made.

I claim—

As a new design, a burial-case that is octagonal in vertical cross-section.

W. F. LANE.
